FLUID CIRCULATING SYSTEM

Stuart A. Courtis and Walter F. Courtis,
Detroit, Mich.

Application March 15, 1937, Serial No. 130,946

7 Claims. (Cl. 137—78)

The present invention relates to a system for circulating fluids and has for its primary object to do away with the use of pumps, injectors and other such mechanical contrivances which are ordinarily used for this purpose.

Another object of the invention is to provide a fluid circulating system, embodying an arrangement of interconnected tanks containing a fluid and means for supplying fluid of a different density thereto under pressure to circulate the first fluid from one set of tanks to another, the system also embodying automatic means which functions when the fluid has been circulated from one set of tanks to another for reversing the order of connections for the purpose of returning the fluid to the tanks from which it was first removed. The circulated fluid, for example, may be water, and the fluid which causes the circulation may, for example, be steam or air.

Another object of the invention is to provide a fluid circulating system utilizing fluids of different density, such as a liquid and a gas or vapor under pressure for circulating the liquid from one set of tanks to a second set and during such circulation passing the liquid through a modifying apparatus, such as a heat exchanger. The invention further aims to automatically reverse the order of connections so that the liquid is returned to the first mentioned tanks, the direction of its flow with respect to the modifying apparatus being the same in both cases, and the flow being controlled with respect to the individual sets of tanks whereby it is constant.

A still further object of the invention is to provide a fluid circulating system of the character above referred to wherein two sources of gas or vapor pressure are used, the first source being a comparatively low pressure and being utilized to charge containers with liquid, and the second source being at comparatively high pressure and being adapted to circulate the liquid from the charged containers through a modifying apparatus.

With the above and other ends in view the invention is more fully disclosed with reference to the accompanying drawings, in which:

Figure 1 is a diagram of the circulating systems;

Figs. 2 and 3 are fragmental diagrams illustrating different operative positions, and

Fig. 4 is a fragmental diagram.

Like characters of reference are employed throughout to designate corresponding parts.

55 The numerals 1 and 2 designate tanks adapted

for the reception of liquid. A pressure supply manifold 3, having an inlet 4 adapted to be connected to a gas or vapor pressure source (not shown) and hereinafter referred to as the first gas pressure source, is connected to the tanks 1 and 2, by branch pipe lines 5 and 6 respectively. As may be seen more clearly in Figs. 2 and 3, a valve 7 is mounted in the branch pipe line 5 and has electromagnets 8 and 9 operatively connected thereto. The electromagnet 8 upon energization thereof functions to open the valve 7 and the electromagnet 9 functions to close the valve, upon energization thereof. The branch pipe line 6 has a similar valve 20 and electromagnets 21 and 22 are operatively connected thereto, the magnet 21 being adapted upon energization thereof to open the valve and the magnet 22, upon energization thereof, being adapted to close the valve.

A pressure exhaust manifold 10 has branch pipe lines 11 and 12 connected to the tanks 1 and 2 respectively. In the branch pipe line 11 is a valve 13 having an electromagnet 14 adapted upon energization thereof to open the valve, and an electromagnet 15 adapted upon energization thereof to close the valve. In the branch pipe line 12 is a valve 16 having an electromagnet 17 operatively connected thereto and adapted upon energization thereof to open the valve, and an electromagnet 18 adapted upon energization thereof to close the valve.

The several electromagnets are operated by electric circuits having controls responsive to predetermined changes in the level of liquid in the container 1. That is, the electromagnets 8, 22, 15 and 17 are in the circuit 23 having a source 24 of E. M. F. and a switch 25 adapted to close the circuit and energize the same. This condition is shown in Fig. 2 wherein the circuit 23 is closed, the electromagnets 8, 22, 15 and 17 are energized, thus closing valves 13 and 20 and opening valves 7 and 16. The other electromagnets 9, 21, 14 and 18 are in the circuit 26 having a source 21 of E. M. F. and a switch 28 adapted to close the circuit when the liquid level in the tank 1 is lowered to that indicated in Fig. 3. When the liquid level reaches approximately the position shown in Fig. 3 the switch 28 closes the circuit 26 (the circuit 23 being open at this time), energizes the electromagnets (9, 21, 14 and 18) to open valves 13 and 20 and close valves 7 and 16.

Referring again to Fig. 1, tanks 1 and 2 have outlet pipe lines 30 and 31 respectively, opening into a conduit 32. Check valves 33 and 34 are

provided in the pipe lines 30 and 31 which function to prevent the flow of liquid from the conduit 32 to the tanks 1 and 2 and to permit the flow of liquid from the tanks 1 and 2 to the conduit. Similar sets of tanks 1a and 2a, 1b and 2b, and 1c and 2c are provided and are connected to the manifolds 3 and 10 and to the conduit 32 in the same manner as the tanks 1 and 2. That is, the tank 1a is connected to the pressure supply manifold 3 by a branch pipe line 5a having a valve 7a therein, to the exhaust manifold 10 by the branch pipe line 11a having the valve 13a therein, and to the conduit 32 by a pipe line 30a having a check valve 33a therein. The tank 2a 10 is connected to the manifold 3 by a branch pipe line 6a having a valve 20a therein, to the manifold 10 by a branch pipe line 12a having a valve 16a therein, and to the conduit 32 by a pipe line 31a having a check valve 34a therein. The tank 2a 15 is connected to the manifold 3 by a branch pipe line 6a having a valve 20a therein, to the manifold 10 by a branch pipe line 12a having a valve 16a therein, and to the conduit 32 by a pipe line 31a having a check valve 34a therein. The tank 1b 20 is connected to the manifold 3 by a branch pipe line 5b having a valve 7b therein, to the manifold 10 by a branch pipe line 11b having a valve 13b therein, and to the conduit 32 by a pipe line 30b having a check valve 33b therein. The tank 2b 25 is connected to the manifold 3 by a branch pipe line 6b having a valve 20b therein, to the manifold 10 by a branch pipe line 12b having a valve 16b therein, and to the conduit 32 by a pipe line 31b having a check valve 34b therein. The tank 1c 30 is connected to the manifold 3 by a branch pipe line 5c having a valve 7c therein, to the manifold 10 by a branch pipe line 11c having a valve 13c therein, and to the conduit 32 by a pipe line 30c having a check valve 33c therein. The tank 2c 35 is connected to the manifold 3 by a branch pipe line 6c having a valve 20c therein, to the manifold 10 by a branch pipe line 12c having a valve 16c therein, and to the conduit 32 by a pipe line 31c having a check valve 34c therein.

It becomes obvious, from the foregoing, that the tanks 1a, 2a, 1b, 2b, 1c and 2c and the pipe lines and valve arrangements relating thereto are identical to the tanks 1 and 2 and their arrangement of the pipe lines and valves. It will be understood, although it is not shown, that the electric circuits and the electromagnets above described are also duplicated in order that the valves 13a, 13b and 13c function in like manner to the valve 13, the valves 7a, 7b and 7c in like manner to the valve 7, the valves 20a, 20b and 20c in like manner to the valve 20, and the valves 16a, 16b and 16c in like manner to the valve 16. As illustrated, however, the liquid levels in the several tanks 1 and 2, 1a and 2a, 1b and 2b, 1c and 2c are not uniform, although they contain like amounts of liquid. Due to this condition the valves relating to the different sets of tanks, although operated in like manner, do not operate at the same time.

The conduit 32 is connected with a modifying apparatus diagrammatically illustrated at 35, and a pipe line 36 having a manual valve 37 connects the modifying apparatus 35 with a modifying apparatus 38. A conduit 39 is connected to the modifying apparatus and extends adjacent the tanks 1 and 2, 1a and 2a, 1b and 2b and 1c and 2c. A pipe line 40 connects the conduit 39 with the tank 1 and has a check valve 41 therein which prevents liquid flow from the tank 1 to the conduit. A pipe line 42 connects the conduit 39 with the tank 2 and has a check valve 43 therein which prevents the flow of liquid from the tank 2 to the conduit 39. Similarly, the conduit 39 is connected to the tank 1a by a pipe line 40a having

a check valve 41a therein, to the tank 2a by the pipe line 42a having a check valve 43a therein, to the tank 1b by the pipe line 40b having the check valve 41b therein, to the tank 2b by the pipe line 42b having the check valve 43b therein, to the tank 1c by the pipe line 40c having the check valve 41c therein, and to the tank 2c by the pipe line 42c having the check valve 43c therein.

The numerals 44 and 45 designate, respectively, 10 a pair of individual tanks. A pressure manifold 46, connected by a pipe line 47 to a source of pressure (not shown), hereinafter termed the second source, has a manual valve 48 therein. The manifold 46 is also connected to the pressure manifold 3 by a pipe line 49 having a manual valve 50 therein. The manifold 46 is connected to the tank 44 by a branch pipe line 51 having a valve 52 therein, and to the tank 45 by a branch pipe line 53 having a valve 54 20 therein, both valves 52 and 54 being electrically operated as will hereinafter appear. An exhaust manifold 55 is connected to the tank 44 by a branch pipe line 56 having a valve 57 therein, and to the tank 45 by a branch pipe line 58 having a valve 59 therein, the valves 57 and 59 also being electrically operated.

Referring to Fig. 4, the valve 52 has an electromagnet 60 connected thereto and adapted upon energization thereof to open the valve, and an electromagnet 61, connected thereto, which is adapted upon energization thereof to close the valve. The valve 54 has connected thereto an electromagnet 62 which is adapted upon energization thereof to open the valve, and an electromagnet 63 which is adapted, when energized to close the valve. Connected to the valve 57 is an electromagnet 64 adapted, when energized, to open the valve, and an electromagnet 65 which is adapted when energized, to close the valve. The valve 59 has an electromagnet 66 for opening the same and an electromagnet 67 for closing the same.

The electromagnets 60, 65, 66 and 63 are in the circuit 68 having a source 69 of E. M. F. and a switch 70 which closes the circuit when the liquid level in the tank reaches the plane shown in Fig. 4. The electromagnets 61, 62, 64 and 67 are in the electric circuit 71 having a source of E. M. F. 72 and a switch 73 adapted to close the circuit to energize the magnets 61, 62, 64 and 67 50 when the liquid level in the tank 44 lowers to the plane of the switch 73.

A conduit 74, having a manual valve 75 therein, is connected to the pipe line 36, adjacent the modifying apparatus 35, and is connected to the tank 45. A check valve 76 is placed in the conduit 74 adjacent the tank 45 and functions to permit the flow of liquid from the conduit to the tank while preventing the flow of liquid from the tank to the conduit. A pipe line 77, having a check valve 78 therein, extends from the tank 45 to the modifying apparatus 79, the modifying apparatus 79 being connected by a pipe line 80 to the tank 44. The pipe line 80 has a check valve 81 which prevents the flow of liquid from the tank 44 thereinto. A conduit 82 is connected to the tank 45 by a branch line 83 having a check valve 84 therein, the conduit 82 also having a check valve 85 and a manual valve 86, and being connected to the pipe line 36 adjacent the modifying apparatus 38.

A set of tanks 44a and 45a are provided and are similar to the tanks 44 and 45 in their association with the system, and although it is not illustrated, it will be understood that the valves 75

to be described are operated by circuits and electromagnets identical to those operating the valves 52, 54, 57 and 59.

As will be seen upon reference to Fig. 1, the tank 44a is connected to the pressure manifold 46 by a branch pipe line 51a having a valve 52a therein and to the exhaust manifold 55 by a branch pipe line 56a having a valve 51a therein. The tank 44a has a branch pipe line 80a, connected to the pipe line 80 and having a check valve 81a therein, and is also connected by the branch pipe line 83a to the conduit 82. The branch pipe line 83a has a check valve 84a therein. The tank 45a is connected to the pressure manifold 46 by a branch pipe line 53a having an electromagnetic valve 54a therein, and to the exhaust manifold 55 by a branch pipe line 58a having an electromagnetic valve 59a therein. The conduit 74 has a branch pipe 74a connected to the tank 45a and provided with a check valve 76a and the pipe 77 has a branch 77a connected to the tank 45a. The branch pipe 77a has a check valve 78a therein.

In describing the first function of the present system it will be assumed that the manual valve 37 is open and the manual valves 75 and 86 are closed. With the several electromagnetic valves 7, 13, 16 and 20 in the position shown in Fig. 2, gas or vapor, under pressure, is admitted to the tank 1, and inasmuch as valve 13 is closed at this time, the gas forces the liquid from the tank 1. The liquid so expelled circulates through the branch pipe 30 and conduit 32 to the modifying apparatus 35, through the pipe line 36 to the modifying apparatus 38 and into the conduit 39. The valve 20 is, at this stage, closed and the valve 16 is open. The gas may exhaust from the tank 2, therefore, and the liquid circulates from the conduit 39 through the branch pipe 42 into the tank 2. When the tank 1 is emptied and the tank 2 is filled, as shown in Fig. 3, the pressure valve 7 closes and the exhaust valve 13 opens. Simultaneously, the pressure valve 20 opens and the exhaust valve 16 closes, and the liquid is forced from the tank 2 and circulates through the conduit 32, the modifying apparatus 35, the pipe line 36 and the modifying apparatus 38 to the conduit 39. Inasmuch as the gas may exhaust from the tank 1 through the valve 13, the liquid flows from the conduit 39 into the tank 1. It becomes apparent, therefore, that the liquid is circulated from one container to the other and that the order of connections is such as to provide a one directional flow.

When the valves 13a and 20a are closed and the valves 7a and 16a open, liquid is forced from the tank 1a into the conduit 32, and flows from the conduit 39 into the tank 2a. When the tank 2a is filled the order of the valves is reversed, and the liquid flows from the tank 2a into the conduit 32 and from the conduit 39 into the tank 1a. When the valves 13b and 20b are closed and the valves 7a and 16a open, liquid is forced from the tank 1b into the conduit 32 and flows from the conduit 39 into the tank 2b until such time as the latter is filled and the valve order reversed. The valves 13c, 20c, 7c and 16c function in like manner with respect to the tanks 1c and 2c.

The order of functioning of the valves relating to the several sets of tanks is such that no two sets of valves change positions at the same time. That is, at the time the valves 7, 13, 16 and 20 change their position from that shown in Fig. 2 to that shown in Fig. 3 the other tanks 1a and

2a, 1b and 2b and 1c and 2c will be filling and emptying, as the case may be. The same condition is present with respect to the valves 7a, 13a, 16a and 20a, valves 7b, 13b, 16b and 20b and valves 7c, 13c, 16c and 20c. With this relationship the liquid flows continuously, due to the fact that when the flow is interrupted momentarily with respect to any pair of tanks liquid flow with respect to the remaining sets of tanks is taking place. The flow is indicated in Fig. 1 by full line and dotted line arrows, the full line arrows indicating the flow when the valves are positioned as shown in Fig. 2, and the dotted line arrows indicating the flow which takes place when the valves are in the position shown in Fig. 3.

During the function of the second stage of the system the valve 37 is closed and the valves 75 and 86 are opened, and the liquid, after leaving the modifying apparatus 35, flows through the conduit 74 and its branch pipe line 74a and into the tanks 45 and 45a when the valves 59 and 59a are open, as shown in Fig. 4. When the valves 59 and 59a are open, the valves 54 and 54a are closed, the valves 57 and 57a which relate to the tanks 44 and 44a are closed and the valves 52 and 52a are open. Therefore, while the liquid enters the tanks 45 and 45a liquid is discharged from the tanks 44 and 44a, the manner in which the tanks 44 and 44a were previously filled being described later.

With the valves in the position shown in Fig. 4, liquid flows from the tank 44 through the branch pipe 83, while other liquid flows into the tank 45, until the switch 72 is actuated, at which time the valves 51 and 54 are opened by their respective electromagnets while valves 52 and 59 are closed. Gas pressure is thus admitted from the second source 47 and forces the liquid from the tank 45 through the pipe line 77 to the modifying apparatus 79, and through the pipe line 80 to the tank 44. When the tank 44 is filled the switch 70 is closed and the order of the valves is again reversed so that the liquid is forced from the tank 44 under pressure from the second source 47, through the branch line 83 and conduit 82 to the modifying apparatus 38, from which the circuit is the same as above described.

Although the controls are not shown in detail, it will be readily understood by those skilled in the art, that the valves 52a, 54a, 57a and 59a function in like manner to the valves 52, 54, 57 and 59 respectively. That is, when the valves 54a and 57a are open and valves 52a and 59a are closed liquid flows from the tank 45a through the branch pipe 77a and the pipe line 77 to the modifying apparatus 79, from which it flows through the conduit 80 and branch pipe line 80a to the tank 44a. When the valves 54a and 57a are closed and valves 52a and 59a are open the liquid flows from the tank 44a through the branch pipe 83a to the conduit 82. It is preferred that while the tank 45 is being filled, as above described, the liquid will be discharged from the tank 45a, and while the tank 45a is filling it will discharge from the tank 45.

From the foregoing, it becomes apparent that the liquid is circulated with respect to the first battery of tanks by pressure from the first source 4 and that the liquid so circulated is circulated through the modifying apparatus 79 by pressure from the second source 47. By closing the valve 48 and opening the valve 50 the liquid may be circulated with respect to the tanks 44, 45, 44a and 45a by pressure from the first source supplied to the manifold 46 through the pipe line 49.

As a matter of convenience in describing and claiming the present invention the pressure supplying fluid is referred to as a gas or vapor, while the circulated fluid is referred to as liquid. It will be understood, however, that the system may be operated where both fluids are of liquid form or where both fluids are of vaporous or gaseous form, provided in both cases that the density characteristics vary to such an extent that they do not mix appreciably. Inasmuch as liquid and a gas or vapor provide common examples of fluids of different densities such terms have been used in describing and claiming the invention.

16 To illustrate the utility of the present device let it be assumed that the whole diagram represents an apparatus for collecting and utilizing radiant energy from a solar source. In such an apparatus, energy in the form of heat is collected 20 from the sun's rays by a liquid and is subsequently extracted from the liquid for the performances of some useful functions. Solar heaters are well known to the public and for this reason a detailed showing of such a heater is 25 deemed unnecessary to an understanding of the invention. It is also known that different liquids are used in such heaters, and that they are sometimes opaque and of quite viscous nature.

In such a heater, the modifying apparatus 30 represents the absorbing agency, or in other words, the liquid in the modifying apparatus is subjected to concentrated sun's rays and is heated. The liquid would be driven in a steady stream from the cylinders 1 and 2, 1a and 2a, 1b 35 and 2b, 1c and 2c, acting alternately in pairs as described above. The liquid would pass slowly in thin tubes and under low pressure in order that it might be heated to a high temperature by absorbed solar energy. By the valve 75 the 40 heated liquid is diverted to the tanks 44, 45, 44a and 45a and is circulated from them under high pressure through the modifying apparatus 79 which would be a heat exchanger. The heat exchanger, as represented by the modifying apparatus 79 would include small thin tubes and the liquid would be moved very rapidly to decrease the skin effect in the tubing and to minimize the losses by radiation. In such a case, the heat from the circulated liquid is utilized 45 to generate steam for example.

From the modifying apparatus or heat exchanger 79 the liquid, with part of the heat extracted therefrom, is circulated as above described to the modifying apparatus 38, which 50 comprises a pre-heater for the water which is converted into steam in the heat exchanger 79. The water circuit is not shown on the drawings.

60 The gaseous medium for circulating the energy collecting liquid might, for example, be compressed air supplied from an outside source.

Although a specific embodiment of the invention has been illustrated and described it will be understood that various changes may be made within the scope of the appended claims 65 without departing from the spirit of the invention, and such changes are contemplated.

What we claim is:

1. In a system of the character described, a plurality of pairs of tanks, each tank having a valve controlled gas pressure inlet and a valve controlled gas pressure outlet, the pressure inlet and outlet valves of one tank of a pair are respectively open and closed when the pressure inlet and outlet valves of the other tank of the

pair are respectively closed and open, each tank having check valve controlled liquid inlets and outlets, a modifying apparatus, means connecting the liquid outlets of all tanks to said modifying apparatus, means connecting the liquid inlets of all tanks to said modifying apparatus, and means individual to each pair of tanks for automatically operating the valves of said gas pressure inlets and outlets of each pair of tanks simultaneously, for alternately supplying gas pressure thereto and exhausting it therefrom to alternately empty said tanks into the first named means and fill said tanks from the second named means, the valves of any pair of tanks being operated at a different time than the time of operation of the valves of any other pair of tanks.

2. In a system of the character described, a plurality of pairs of tanks, each tank having a valve controlled gas pressure inlet and a valve controlled gas pressure outlet, the pressure inlet and outlet valves of one tank of a pair are respectively open and closed when the pressure inlet and outlet valves of the other tank of the pair are respectively closed and open, each tank having check valve controlled liquid inlets and outlets, a modifying apparatus, means connecting the liquid outlets of all tanks to said modifying apparatus, means connecting the liquid inlets of all tanks to said modifying apparatus, means individual to each pair of tanks for operating the valves of said gas pressure inlets and outlets of each pair of tanks simultaneously, for alternately supplying gas pressure thereto and exhausting it therefrom to alternately empty said tanks into the first named means and fill said tanks from the second named means, the valves of any pair of tanks being operated at a different time than the time of operation of the valves of any other pair of tanks, and means responsive to predetermined changes in the liquid level in one tank for automatically operating said last named means.

3. In a system of the character described, a pair of tanks, each tank having a valve controlled gas pressure inlet and a valve controlled gas pressure outlet, said inlets being connected to means for supplying gas pressure thereto, each tank having a check valve controlled outlet connected to a common conduit and a check valve controlled inlet connected to a second common conduit, means for operating said valve controlled gas inlets and outlets alternately whereby gas pressure exhausts liquid from one tank into the first conduit and exhausts from the other tank whereby liquid flows from the second conduit thereinto, a second pair of tanks, each tank of said second pair having a valve controlled gas pressure inlet connected to a second means for supplying gas pressure and a valve controlled outlet, each tank of the second pair having check valve controlled liquid inlets and outlets, means connecting the liquid inlet of the first tank of said second pair to said first conduit, a modifying apparatus, means connecting the liquid outlet of said first tank to the inlet of said modifying apparatus, means connecting the outlet of said modifying apparatus to the liquid inlet of the second tank of said second pair, means connecting the outlet of said second tank to said second conduit, and means for operating said valve controlled inlets to alternately supply gas pressure from the second source to the tanks of said second pair and for exhausting such gas pressure therefrom.

4. In a system of the character described, a pair of tanks, each tank having a valve controlled gas pressure inlet and a valve controlled gas pressure outlet, said inlets being connected to means for supplying gas pressure thereto, each tank having a check valve controlled outlet connected to a common conduit and a check valve controlled inlet connected to a second common conduit, means for operating said valve controlled gas inlets and outlets alternately whereby gas pressure exhausts liquid from one tank into the first conduit and exhausts from the other tank whereby liquid flows from the second conduit thereto, a second pair of tanks, each tank of said second pair having a valve controlled gas pressure inlet connected to a second means for supplying gas pressure and a valve controlled outlet, each tank of the second pair having check valve controlled liquid inlets and outlets, means including a modifier connecting the liquid inlet of the first tank of said second pair to said first conduit, a modifying apparatus, means connecting the liquid outlet of said first tank to the inlet of said modifying apparatus, means connecting the outlet of said modifying apparatus to the liquid inlet of the second tank of said second pair, means connecting the outlet of said second tank to said second conduit, and means for operating said valve controlled inlets to alternately supply gas pressure from the second source to the tanks of said second pair and for exhausting such gas pressure therefrom.
5. In a system of the character described, a pair of tanks, each tank having a valve controlled gas pressure inlet and a valve controlled gas pressure outlet, said inlets being connected to means for supplying gas pressure thereto, each tank having a check valve controlled outlet connected to a common conduit and a check valve controlled inlet connected to a second common conduit, means for operating said valve controlled gas inlets and outlets alternately whereby gas pressure exhausts liquid from one tank into the first conduit and exhausts from the other tank whereby liquid flows from the second conduit thereto, a second pair of tanks, each tank of said second pair having a valve controlled gas pressure inlet connected to a second means for supplying gas pressure and a valve controlled outlet, each tank of the second pair having check valve controlled liquid inlets and outlets, means connecting the liquid outlet of said first tank to the inlet of said modifying apparatus, means connecting the outlet of said modifying apparatus to the liquid inlet of the second tank of said second pair, means connecting the outlet of said second tank to said second conduit, and means for operating said valve controlled inlets to alternately supply gas pressure from the second source to the tanks of said second pair and for exhausting such gas pressure therefrom.
6. In a system of the character described, a pair of tanks, each tank having a valve controlled gas pressure inlet and a valve controlled gas pressure outlet, said inlets being connected to means for supplying gas pressure thereto, each tank having a check valve controlled outlet connected to a common conduit and a check valve controlled inlet connected to a second common conduit, means for operating said valve controlled gas inlets and outlets alternately, whereby gas pressure exhausts liquid from one tank into the first conduit and exhausts from the other tank whereby liquid flows from the second conduit thereto, a second pair of tanks, each tank of said second pair having a valve controlled gas pressure inlet connected to a second means for supplying gas pressure and a valve controlled outlet, each tank of the second pair having check valve controlled liquid inlets and outlets, means connecting the liquid inlet of the first tank of said second pair to said first conduit, a modifying apparatus, means connecting the liquid outlet of said first tank to the inlet of said modifying apparatus, means connecting the outlet of said modifying apparatus to the liquid inlet of the second tank of said second pair, means connecting the outlet of said second tank to said second conduit, and means for operating said valve controlled inlets to alternately supply gas pressure from the second source to the tanks of said second pair and for exhausting such gas pressure therefrom.
7. In a system of the character described, a pair of tanks, each of said tanks having an inlet and an outlet for fluid and having a second inlet and a second outlet for other fluid under pressure, a modifying apparatus, means connecting said first-named outlets of each tank to said modifying apparatus, means connecting said first-named inlets of the tanks to said modifying apparatus, valve means controlling said second-named inlets, valve means controlling said second-named outlets, and means to control operation of said valves and operable in response to predetermined changes of a physical characteristic of the first-mentioned fluid in one of said pair of tanks said inlet and outlet valves of one tank of a pair of tanks being respectively opened and closed when the inlet and outlet valves of the other tank of the pair of tanks are respectively closed and opened.

STUART A. COURTIS.
WALTER F. COURTIS. 60
